FLASHLIGHT

Robert F. Moore, Rte. 1, Box 308, Shelby County,
near Waldron, Ind.

Filed Apr. 14, 1964, Ser. No. 359,613
1 Claim. (Cl. 240—10.6)

This invention relates to an electric lamp, and more specifically to what is commonly termed a flashlight. The invention involves the use of a lamp bulb of a certain rated voltage in combination with a battery delivering a voltage much higher than that of the rated voltage of the lamp bulb, and in this relationship, there is means provided for preliminarily heating the low voltage lamp bulb element to bring it up gradually whereby the greater voltage of the battery may be employed to increase the illuminating effect of the lamp bulb.

Also the invention includes the specific means for transmitting the current from the battery which is located externally of the flashlight, doing so through a plug and jack combination wherein the plug is of the elongated nature and extends substantially at right angles from the housing of the flashlight, and then also including in the electrical circuit a rheostat having a control extending from that housing at right angles to the plug.

The flashlight involved in this invention would be employed among other usages as an illuminating means in night hunting in walking through the woods, the flashlight would be so controlled as to give a substantially normal beam of light, and then when game is located, the illumination directed from the flashlight may be quickly increased, so that the game such as a raccoon normally high up in a tree could be located, and the flashlight held along the side of, but preferably under a rifle or other gun so that the beam of light of the high intensity is on the animal while the gun is sighted.

Of course the flashlight would have many other usages, but this particular example, the extending plug forms a means for abutting the operator's hand thereagainst when the plug is turned downwardly, and then the voltage controller element protruding from the side of the flashlight is turned at right angles to the axis of that plug, extending from the flashlight from its left hand side when held by a right hand operator in his left hand, so that the rheostat control member may be manipulated by the fingers and thumb of the operator to adjust the flashlight to the intensity of light beam desired.

Further advantages and purposes of the invention will become apparent to those versed in the art in the following description of one particular form of the invention as illustrated in the drawing, in which

FIG. 1 is a view in top plan of a flashlight embodying the invention;

FIG. 2 is a view in left hand side elevation and including an external battery and carrier;

FIG. 3 is a view in front end elevation of the flashlight; and

FIG. 4 is a wiring diagram.

A flashlight generally designated by the numeral 10 has an elongated tubular body 11 with a bulbous front end portion 12 within which an incandescent lamp 13 is mounted centrally of a reflector 14, all as is well known to those versed in the art. The lamp bulb 13 is of a low voltage type, such for example without limitation thereto as the usual six-eight volt bulb.

The battery 15 is of the long type variety and is preferably of the dry cell construction. In the present form of the invention, this battery 15 has a rated output of twelve volts. This of course may vary as the operator may desire, so long as the output exceeds the rated capacity of the lamp bulb 13. The battery 15 is preferably

2

carried in a container 16 to which is attached a shoulder strap 17 so that the battery may be conveniently carried swung from the shoulder of the operator.

A coiled, flexible cable 18 comprising of a multiple number of turns leads from the two terminals 19 and 19a of the battery to a plug 20 of the usual and well known type for interconnecting one part of a circuit through the plug 20 to a jack 21. The jack 21 is within the tube 11, preferably near the rear end. As indicated, the plug 20 is entered and maintained in removable relation with the jack 21 to be at right angles to the tube 11, that is the axis of the plug 20 is normal to the longitudinal axis of the tube 11.

There is a cut-off switch 22 mounted on the top side of the tube 11 in relation to the plug 20 extending downwardly therefrom. This switch 22 is also of the usual and well known type employed in conjunction with flashlights, and is permanently affixed to the tube 11.

A further element is added. This element designated by the numeral 23 is essentially a rheostat and has a controlling shaft 24 extending outwardly from the tube 11 near its forward end, and preferably under the switch 22 to extend generally perpendicular to the axis of the tube 11, and to be at right angles to the plug 20.

Referring to the electrical circuit diagrammed in FIG. 4, the terminals of the battery 15 are connected with the plug 20 in the usual manner, and the plug 20 is engaged with the jack 21. This circuit from the jack 21 consists of the wire 25 and the wire 26, which include therebetween in series the switch 22, the rheostat 23, and the lamp bulb 13.

In operation, the battery strap 17 may be swung over the shoulder of the operator, and the plug 20 engaged with the jack. Normally the rheostat 23 would be adjusted to the shaft 24 to be set for a full complete resistance included in the circuit so that there would be no visible illumination of the lamp 13, and the switch 22 under such condition would be closed, and normally left closed during use of the flashlight 10. When the flashlight is to be used simply as illumination of the ground or terrain over which the operator is walking, the shaft 24 will be rotated only sufficiently to give illumination for visibility to that terrain. This illumination would be such as would be had, for example, as between four and six volts across the lamp terminals.

Then when a far reaching and more brilliant beam of light is desired, the rheostat shaft 24 will be rotated around gradually to supply less resistance in series in the circuit so that more voltage from the battery is actually applied to the lamp 13, even up to the full twelve volts of the battery in the example described herein. This higher voltage on the low voltage rated lamp is permissible since the heating of the lamp is gradual, and the full voltage is not applied instantaneously, otherwise the lamp filament would be burned out immediately. The lamp filament is however of sufficiently rugged construction in the normal lamp as to permit this application of the higher voltage in the manner indicated.

In holding the flashlight 10 in the left hand as above indicated, the palm of the hand may be abutted by one edge against the protruding plug 20 so as to give a firm positioning of the lamp 10 in the hand, whereupon the thumb will come up and around adjacent to the rheostat shaft 24, and at least the index and the second fingers will be brought around so that the shaft 24 may be manipulated between the thumb and one or both of those fingers to give the desired voltage application to the circuit. In other words, the flashlight is designed to be carried and operated by one hand. Referring to FIG. 2, the carrying bag 16 is broken away at the top to show the uppermost end of the battery 15, and normally there will be a retaining strap 26 over the top of the battery, but here

shown as only as a fragmentary attaching end 26a in order to prevent concealing the upper end of the battery.

While I have herein shown and described my invention in the one particular form, it is obvious that structural changes may be employed without departing from the spirit of the invention, and I therefore do not desire to be limited to this precise form beyond the limitations which may be imposed by the following claim.

I claim:

A flashlight comprising the combination with
a body,
a lamp bulb normally operated on a rated voltage and
mounted at one end of the body; and
a switch mounted on the body:

of
15
a portable battery having a rated output voltage
higher than that of said bulb;
a jack carried by said body;
a plug removably received by said jack;
a flexible cable interconnecting said battery and said
20
plug;
a rheostat carried by said body and operated by a shaft;
said plug engaging said jack at approximately a right
angle to said body;
said shaft extending from said body at approximately

10

15

a right angle thereto at a position approximately
ninety degrees around from the plug and spaced
intermediate the plug and said bulb;
said switch being spaced at approximately one hundred
80 degrees around from said plug and intermediate
said plug and said bulb; and
a circuit from said battery through said cable including
in series said lamp, said switch, said rheostat,
and said jack;
said rheostat normally set to provide minimum current
flow through said lamp upon a closed switch, and,
upon turning of said shaft permitting increased
battery voltage to be impressed upon said lamp bulb.
